CYLINDRICAL CONTAINER CARRIER

Clifford R. Keeslar, Kalamazoo, Mich., assignor to Wm. John Upjohn Associates, Kalamazoo, Mich., a proprietorship of Michigan

Filed Sept. 7, 1962, Ser. No. 71,590

Term of patent 14 years

(Cl. D58—26)

FIG. 1 is a front perspective of a cylindrical container carrier, showing my new design, the rear thereof being the same in appearance.

FIG. 2 is a top plan view of the cylindrical container carrier.

FIG. 3 is a front elevational view of the cylindrical container carrier.

FIG. 4 is a side elevational view of the cylindrical container carrier.

The characteristic feature of my cylindrical container carrier resides in the portions thereof shown in full lines and consists primarily in the integral strap-like supporting members which bisect each of the angles of the two open ends, the straps of each end meeting at a central point in the open end substantially as shown.

The opposite end is like the end shown, and the broken line showing of the containers is for illustrative purposes only.

I claim:

The ornamental design for a cylindrical container carrier, substantially as shown and described.
